CLAIM

The ornamental design for a coffee brew basket, as shown and described.

DESCRIPTION

FIG. 1 is a top left front perspective view of a coffee brew basket showing my new design;

FIG. 2 is a bottom right front perspective view thereof;

FIG. 3 is a front elevational view thereof;

FIG. 4 is a rear elevational view thereof;

FIG. 5 is a left side elevational view thereof;

FIG. 6 is a right side view thereof;

FIG. 7 is a bottom view thereof;

FIG. 8 is a top view thereof;

FIG. 9 is a cross-sectional view thereof taken along line 9—9 in FIG. 8; and,

FIG. 10 is a top right front perspective view thereof.

The broken line showing of a handle in FIGS. 1,2, and in an alternate position in FIG. 10 is for illustrative purposes only and forms no part of the claimed design.

The dashed lines shown in FIGS. 1,2 and 10 represent environmental elements only and form no part of the claimed design.
